MAN-LIKE MODEL TO AID IN TEACHING
THE MARTIAL ART OF KARATE

Eddy D. Field II, 4014 Van Nord Ave.,
Studio City, Calif. 91604

Filed July 25, 1966, Ser. No. 3,195

Term of patent 14 years

(Cl. D34—4)

Fig. 3

I claim:

The ornamental design for a man-like model to aid in teaching the martial art of karate, substantially as shown.
